UNITED STATES PATENT OFFICE.

EDWARD H. McCLOUD, OF COLUMBUS, OHIO.

OPERATING DEVICE FOR FLEXIBLE ROLLER-SHUTTERS.

No. 878,659.

Specification of Letters Patent.

Patented Feb. 11, 1908.

Application filed June 9, 1906. Serial No. 320,995.

To all whom it may concern:

Be it known that I, EDWARD H. McCLOUD, a citizen of the United States, residing at Columbus, in the county of Franklin and 5 State of Ohio, have invented certain new and useful Improvements in Operating Devices for Flexible Rolling Shutters; and I do hereby declare the following to be a full, clear, and exact description of the invention, such 10 as will enable others skilled in the art to which it appertains to make and use the same.

One object of the invention is to provide an improved roller support and operating mechanism for flexible rolling shutters, and a 15 further object is to improve the construction of frame and runway in which such shutters are guided.

In the accompanying drawings the invention is shown in its application to a shutter 20 constructed of wooden slats, but shutters of other material can be used, and the invention is not limited to the precise form and details of construction shown.

In said drawings—Figure 1 is a vertical 25 sectional view, through the shutter roller and shutter, the operative mechanism being shown partly in full and partly in broken lines; Fig. 2 is a partial front view of the shutter and operative parts, the latter being 30 shown in full; Fig. 3 is a side elevation on a reduced scale with parts broken away; Fig. 4 is a front view of the right hand end of the device, parts being broken away to show details of construction; Fig. 5 is a view of the 35 inner side of the right hand end of the device with some of the parts removed and some broken away.

In the several views 1 designates the shutter roller or drum of any appropriate construction provided with end stud shaft 1^a extending through slots 2, 2 in end brackets 3 and 3^a secured above a door or other opening as usual. The roller shown is of the hollow form adapted to contain a counterbalancing 45 spring, if desired, my invention being applicable to rollers with or without counterbalancing devices. The slots 2, 2 are inclined upwardly and outwardly on an arc of a circle the outer ends of said slots limiting 50 the outward movement of the roller. The stud shafts 1^a of the roller 1 are journaled in rocking arms 5 and 5^a which arms are pivotally mounted on pins 1^b and 1^c, respectively, fixed in the brackets 3 and 3^a. It will be observed that the rocking arms 5 and 5^a are 55 pivoted at points below the higher ends of

the slots 2, or below the points where the roller will contain the greatest weight of the curtain. This construction facilitates the movement of the roller by gravity to a position where the curtain shall extend in the channels tangent to the roller. The mechanism for rotating the roller 1 whereby the shutter is wound thereon comprises a large gear wheel 6 fixed to the stud shaft 1^a of the 60 shutter roller, an intermediate gear 8 loosely mounted on the pin 1^b and meshing with said large gear 6, a pinion 7 in engagement with said intermediate gear 8 and fixed to a shaft 9 which shaft is journaled in a bracket arm 65 10 extending from said bracket 3, said shaft 9 having secured thereto a sprocket wheel 11 adapted to be driven by a chain 12. Because the arc of movement of the shaft 1^a has for its center the center of the pin 1^b, the 70 75 large gear 6 is in constant engagement with the intermediate gear 8 and the curtain can be operated in all its positions.

Secured to the brackets 3 and 3^a opposite the shutter roller are small antifriction rollers 80 14 for the purpose of guiding the curtain in its ascent and descent and relieving the friction thereof in its passage into or out of the channel. Instead of having separate rollers 14, one roller 14^a may be employed 85 extending entirely across the space between the vertical guideways or channels for the shutter.

The shutter and operating devices and also the channel frame are shown as secured to 90 the inside of a doorway. In order to close the opening above the channel and between the door frame and shutter to prevent the entrance of dust and rain into the room I provide a bar 15 secured to the bracket arms 95 3 and 3^a and extending across the doorway above and in front of the channels. The bar 15 is preferably formed with an upwardly projecting flange 16 bent away from the channel and adapted to guide the shutter and prevent friction at the openings into the channels. When a continuous roller 14^a is employed extending entirely across the space 100 between the channels the bar 15 may be dispensed with as the roller serves the purpose 105 of closing the space.

In operating the device to wind up the shutter the sprocket wheel 11 is rotated in the direction indicated by the arrow, whereby, through the train of gearing referred to, 110 the large gear connected with the roller shaft, and consequently the roller, are rotated.

The antifriction devices referred to are so located with reference to the roller that they have constant bearing upon the shutter as it is rolled upon or from the roller. Hence, as 5 the shutter is wound up its contact with the antifriction rollers forces the shutter roller and shutter laterally and outwardly in the elongated slots. The antifriction rollers are also so constructed and located that the inner edges of the shutter channels are in a 10 vertical line tangent to the roller surface, hence the unwound portion of the shutter hangs by its own weight always in a vertical line both in and above the channels, thus 15 tending to prevent friction and wear of the parts and facilitating the manipulation of the device.

What I claim and desire to secure by Letters Patent is:

- 20 1. The combination with a flexible rolling shutter and channel therefor, of a roller for the shutter, an arm pivoted below said roller and engaging a bearing thereof, end brackets provided with slots to receive the bearings of 25 the roller and in which said bearings move, said slots being inclined downwardly towards the channel and terminating at their upper ends in a plane substantially vertically above the pivot of said arm whereby the upward movement of the roller is limited to 30 said vertical plane, and said roller and shutter thereon being free to move of their own weight toward said channel when the shutter unrolls, and means for rotating the roller.
- 35 2. In combination with the roller of a flexible rolling shutter, said roller being laterally movable, a pivoted arm engaging a bearing of the roller and movable therewith, a gear mounted on the end of said roller, a second 40 gear having a fixed axis of rotation and engaging the first-mentioned gear, the axis of movement of said pivoted arm also coinciding with the axis of rotation of the second-mentioned gear.
- 45 3. In combination with the roller of a flexible rolling shutter, said roller being laterally movable, an arm pivoted below the horizontal plane of the axis of the roller and engaging a bearing of the roller and movable therewith, a gear mounted on the end of said roller, and a second gear having a fixed axis of rotation and engaging the first-mentioned gear.
- 50 4. In combination with the roller of a flexible rolling shutter, said roller being laterally movable, a pivoted arm engaging a bearing of the roller and movable therewith, a spur gear mounted on the roller, a spur gear to engage the first-mentioned spur gear and having a fixed axis of rotation, a spur pinion to drive

the second-mentioned gear, and a sprocket 60 wheel carrying a chain mounted to operate the pinion.

5. In combination with the roller of a flexible rolling shutter, said roller being laterally movable, a pivoted arm engaging a bearing of 65 the roller and movable therewith, a spur gear mounted on the roller, a spur gear to engage the first-mentioned spur gear and having a fixed axis of rotation, and means to operate the second-mentioned gear including a 70 sprocket wheel and chain.

6. In combination with a flexible shutter and roller therefor, of end brackets having openings in which said roller moves, pivoted bracket arms in which said roller is journaled, means for rotating said roller, and anti-friction devices adapted to engage the shutter whereby as the latter is wound upon its roller the said roller and shutter thereon are moved laterally in said openings. 75

7. In combination with a flexible shutter and roller therefor, of vertical channels or guides for said shutter, end brackets having openings in which the bearings of said roller move, pivoted bracket arms in which said roller is journaled, means for rotating said roller, and an antifriction roller extending between said channels and adapted to engage the shutter whereby as the latter is wound upon its roller the said roller and shutter 80 thereon are moved laterally in said openings. 85

8. In combination with the frame of a door-way or other opening, a flexible shutter and roller therefor, end brackets, vertical guides for said shutter, an angle bar extending horizontally between said vertical guides and the upper part of the door frame, means for rotating said roller to wind the shutter, said roller and the shutter thereon being movable laterally with respect to said guides. 95

9. In combination with the frame of a door-way or other opening, a flexible shutter and roller therefor, vertical guides for said shutter, a bar extending horizontally between said vertical guides and the upper part 105 of the door frame or opening and provided on its edge adjacent the vertical guides with an upwardly extending and outwardly curved flange, means for rotating said roller to wind the shutter, said roller and shutter thereon being movable laterally with respect to said guides. 110

In testimony whereof I affix my signature, in presence of two witnesses.

EDWARD H. McCLOUD.
